US0D1051958S

(12) **United States Design Patent** (10) Patent No.: **US D1,051,958 S**
Vettermann (45) Date of Patent: **** Nov. 19, 2024**

(54) **TOOL FOR DRILLING, MILLING, OR DIGGING**

(71) Applicant: **Gühring KG**, Albstadt (DE)

(72) Inventor: **Richard Vettermann**, Rodewisch (DE)

(**) Term: **15 Years**

(21) Appl. No.: **35/516,412**

(22) Filed: **Feb. 17, 2023**

(80) **Hague Agreement Data**

Int. Filing Date: **Nov. 17, 2022**

Int. Reg. No.: **DM/226787**

Int. Reg. Date: **Feb. 17, 2023**

Int. Reg. Pub. Date: **Feb. 24, 2023**

CLAIM

The ornamental design for a tool for drilling, milling, or digging as shown and described.

DESCRIPTION

1.1 is a top, front, left side perspective view of a tool for drilling, milling, or digging showing the new design;

1.2 is a front view thereof;

1.3 is arear view thereof;

1.4 is a left side view thereof;

1.5 is a right side view thereof;

1.6 is a top view thereof; and

1.7 is a bottom view thereof.

1 Claim, 6 Drawing Sheets
